UNITED STATES PATENT OFFICE.

FRED FANDREI, OF STURGEON BAY, WISCONSIN.

SCOOP.

1,297,132.

Specification of Letters Patent. Patented Mar. 11, 1919.

Application filed May 25, 1918. Serial No. 236,603.

To all whom it may concern:

Be it known that I, FRED FANDREI, a citizen of the United States, residing at Sturgeon Bay, in the county of Door and State 5 of Wisconsin, have invented certain new and useful Improvements in Scoops, of which the following is a specification.

The invention has for an object to effect improvements in scoops for use in dredges 10 and excavating devices, the specific embodiment shown herein being adapted to use in excavating, and for the handling of manure, straw and the like, in lifting the same from a bank or dump, and depositing it upon a 15 carrier or otherwise. It is a particular aim of the invention to effect improvements in the means whereby an excavating unit of the clam shell type may be improved in construction and function, and I aim to improve 20 the mounting of the opposed elements of such a device whereby a minimum of power will be required for its operation. A further aim is to improve the manner of attaching teeth elements to such devices and 25 to adjust the teeth to compensate for wear. A further aim is to effect an improvement in the construction of the bucket elements, as receptacles, making them adaptable to handle such material as gravel, sand and 30 earth, or straw and manure, without involving structural modifications of the device, or removal of parts.

Additional objects, advantages and features of invention may appear from the construction, arrangement, and combination of parts hereinafter described, and shown in 35 the drawings, wherein,

Figure 1 is a side elevation of the bucket constructed in accordance with my invention,

Fig. 2 is a cross sectional view thereof, on the line 2—2 of Fig. 1.

There is illustrated an excavator device including shell or bucket elements 10 and 11 45 which may be carried by any desired form of hoist, and in the present instance are illustrated as supported by a boom element 12, the outer extremity only of which is shown. At the extremity of the boom element 50 a frame piece 13 is secured, having a substantially U-shaped portion with arms extended downwardly, their lower ends being bent outwardly. Upon the frame piece there are secured plates 15, having at each 55 end apertured ears 16 in which there are pivoted hangers 17, the lower ends of which

are suitably engaged with clearing bails 18 extended around the inner sides of respective bucket elements 19, which include side portions 20 cut away at their outer opposed 60 edge portions as shown at 21, to form a large clear way through the bucket from side to side, and an intermediate bottom wall portion 22 formed integrally therewith, or otherwise, as may be preferred, in the form 65 of a segment of a cylinder, the portions 22 of the opposed bucket elements being adapted to meet snugly at their opposed edges when in abutment, to completely close the lower part of the buckets, at times. The 70 sides 19 of the bucket elements are extended upwardly a considerable distance above the lower ends of the hangers 17 as shown in Fig. 1, and at their uppermost parts are provided with respective meshed gear segments 23 at each side, suitably fixed to the bucket elements and upon shafts 23' in respective bucket elements, these shafts having operating arms 24 and 25, respectively, the first mentioned arm being upon the outermost shaft with respect to the beam 12, and being extended diagonally upwardly and outwardly when the bucket is in closed position, while the one 25 is extended inwardly, nearly horizontal or at a suitable 85 angle to the arm 24 for the functions to be described. A cable 26 is suitably anchored upon the arm 25, and extended outwardly around a pulley 27 at the extremity of the arm 24, thence inwardly beside the beam 12, 90 so that when drawn upon, the arm 24 will be forced inwardly and the arm 25 drawn outwardly, causing opening action of the bucket.

The gears serve to synchronize the movement of the bucket elements and insure the same movement in each, relatively to the horizontal. Fixed upon the bucket elements there are respective closing arms 30, at each side, and to those arms upon the inner 100 bucket elements cables 31 are attached, extended forwardly and thence rearwardly around pulleys 32 upon the arms of the forward bucket element, the arms being so positioned that the pulleys 32 and ends of the 105 opposite arms 30 are located closely together at each side when the bucket is in closed position, as shown in Fig. 1. The cables 31 may be operated in any suitable way to draw the arms toward each other, and thus close 110 the buckets. The shafts 23' are eccentric to the walls 22, being considerably above the

centers of the bucket elements when closed. Pivoted at each side of each bucket element on an axis concentric with the outer wall 22 in each instance there are end gates 35, lying close against the sides 19 and 20, and exteriorly thereof, each having edges 36 adapted to abut snugly in line with the opposed bottom edges of the walls 22 and thereby close the openings 21 at times when 10 the bucket is in closed position.

Upon the sides 19 and 20, adjacent their outer parts, pulleys 38 are mounted, and upon the sides closely adjacent the shaft 23', pulleys 39 are mounted, while vertically over 15 the last mentioned pulleys similar pulleys 40 are mounted upon the frame piece or yoke 13. Connected to the upper edges of the gate elements 35, there are cables 41 extended upwardly and over the adjacent pulley 38, and thence inwardly and upwardly at the inner side of the pulley 39, whence the cables are extended upwardly and over the pulleys 40 to a suitable draft connection 42, which includes a spring 43 and pulley block 44, the cables from opposite gates 35 on each side of the bucket being continued, and carried through the pulley block 44.

Upon the outer side of each bucket element there is a slidable fork device 44', having a 30 multiplicity of tines 45, adapted to be projected beyond the edges 22' of the bucket elements and at right angles to said edges, the tines and the complete fork device being curved to strike against the sides of the 35 bucket elements, and being suitably connected at their outer parts whereby they will be held in rigid mutual relation. The fork elements are held close against the under sides of the bucket elements by means of 40 suitable guide brackets 46, and closely adjacent the lower ends of the tines, guard pieces 47 are connected therewith, having keeper flanges 48 extended upwardly a short distance on each side of the bucket elements to 45 prevent lateral displacement of the tines, and if desired the guard elements 47 may be made adjustable longitudinally upon the tines 45. For this purpose certain of the tines may be beveled at adjacent sides to receive a clamping block 48' secured to the 50 guard 47, and between the remainder of the tines, lugs 49 may be formed upon the guard 47 snugly and slidably fitted between the

tines, whereby laterally relative displacement of the tines is prevented. At their 55 outer upper parts, the fork elements 44' are provided with gear segments 50 meshed with which there are respective gears 51, carried upon transverse shafts 52 provided with operating handles 53, by which means the fork 60 elements may be adjusted upon the bucket elements to project the tines or retract them as desired.

What is claimed:

1. A device of the character described 65 comprising a support, bucket elements pivoted thereon having curved intermediate portions, and side portions, said side portions having open portions at their inner parts, whereby when the bucket elements 70 are in closed position a clear way is formed through the device, gates pivoted on the sides concentrically with said intermediate portion the adjacent gates on opposed elements being movable into position for coengagement when the bucket elements are in closed position to close said clearway through the device, means to operate the bucket elements and means to operate the 75 gates.

2. A device comprising a support, pivoted buckets thereon constructed for coaction to engage material for lifting, including curved intermediate bottom portions, slidable fork elements thereon having tines positioned 85 to extend at right angles to the medial plane between the buckets, and movable for projection and retraction of said tines, means to move the fork elements, and means to 90 secure them in adjusted position.

3. An excavator device comprising a body frame, a plurality of pivoted bucket elements thereon for closing coaction, respective intermeshed gear elements on the bucket elements concentric with their pivots, arms 95 connected respectively thereto arranged to extend at an angle to each other when the bucket elements are in closed position and in position for convergent movement to open said elements.

In testimony whereof I have affixed my signature in presence of two witnesses.

FRED FANDREI.
